(57) **CLAIM**

The ornamental design for an automobile body, as shown and described.

DESCRIPTION

FIG. 1 is a front perspective view of an automobile body showing our new design;

FIG. 2 is a side view thereof;

FIG. 3 is a front view thereof;

FIG. 4 is a rear view thereof;

FIG. 5 is a rear perspective view thereof; and,

FIG. 6 is a top plan view thereof.

It will be understood that the broken lines presented in the drawings are for illustration only, and do not form a part of the claimed design.
